Patented Nov. 30, 1976

242,555

X-RAY FLUORESCENCE SPECTROMETER

David J. McCaa, Stevensville, Mich., assignor to
Leco Corporation, St. Joseph, Mich.

Filed Mar. 17, 1975, Ser. No. 558,666

Term of patent 14 years

Int. Cl. D24—01

U.S. Cl. D32—2 C

FIG. 1.

FIG. 2.

FIG. 3.

FIG. 4.

FIG. 5.

FIG. 6.

FIG. 1 is a front elevational view of an X-ray fluorescence spectrometer;

FIG. 2 is a left side elevational view thereof;

FIG. 3 is a right side elevational view thereof;

FIG. 4 is a rear elevational view thereof;

FIG. 5 is a top plan view thereof; and

FIG. 6 is a front perspective view thereof.

I claim:

The ornamental design for an X-ray fluorescence spectrometer, substantially as shown.
